UNITED STATES PATENT OFFICE.

PLINY E. HOLT, OF STOCKTON, CALIFORNIA, ASSIGNOR TO THE HOLT MANUFACTURING COMPANY, OF STOCKTON, CALIFORNIA, A CORPORATION OF CALIFORNIA.

TRACTOR.

1,336,961.

Specification of Letters Patent. Patented Apr. 13, 1920.

Application filed October 1, 1917. Serial No. 194,253.

To all whom it may concern:

Be it known that I, PLINY E. HOLT, a citizen of the United States, residing at Stockton, in the county of San Joaquin and State 5 of California, have invented new and useful Improvements in Tractors, of which the following is a specification.

This invention relates to tractors of the self-laying track type; and has for its object to provide a truck construction for the track such that ditches, shell holes and depressions, and steep embankments can be negotiated with comparative ease, whereby to adapt the machine especially for use as 15 a gun mount for traveling over rough or broken terrene such as is encountered in the field of war.

Tractors of this type employ exceedingly long tracks ranging from eight to fourteen 20 feet from center to center of the carrying wheels. With a rigid truck frame the track spans the ditch or depression, and its tractive surface is therefore limited to the ends of the tracks, the intermediate portion of 25 the track being at this time out of engagement with the ground. Also when embankments are encountered the front end of the track, where a rigid truck frame is employed, is liable to dig its way into the earth 30 and stall the machine.

In the present invention I hinge the truck frame intermediate its ends in such a way that it will be free to move downwardly away from the main frame of the machine 35 and enable the track to conform to the depressions in the ground, so that the maximum tractive surface of the machine will be maintained. Also the front truck section, which carries a guide or idler wheel for the 40 front portion of the track, is so arranged that it will flex upwardly when striking an embankment and prevent digging in of the front portion of the track. The angle which the front truck section is capable of assuming is such that the track will readily pass over embankments which are practically vertical.

One form which my invention may assume is exemplified in the following description and illustrated in the accompanying drawings, in which—

Figure 1 shows a side elevation of a device embodying my invention.

Fig. 2 shows a plan view of the same.

Fig. 3 shows a diagram illustrating the

position assumed by the truck sections in passing over a depression or climbing an embankment.

Fig. 4 shows a plan view of the pivotal connection for the front truck. 60

Fig. 5 shows a modified form of connection of the rear truck to the chassis.

Fig. 6 shows a modified construction of the device.

The machine, as here shown, comprises a 65 main frame 10, of suitable construction, supported at its sides upon a pair of endless, flexible, self-laying track mechanisms. Each track mechanism includes a driving sprocket wheel 11 at the rear fixed upon one end of a 70 driving shaft 12, which shaft is journaled on the main frame. A hinged truck frame, consisting of front and rear sections 13 and 14, respectively, supports the weight of the main frame, and each truck frame carries a 75 series of flanged rollers 15, the rear one being shown as having six and the front one as having three. The rear section is in no way connected to the rear driving sprocket wheel and is slidably and pivotally connected to the main frame, as will presently appear. The front section is pivoted intermediate its ends upon one end of a transverse shaft 16 through the medium of a 80 spring mounted bearing presently to be described; the said shaft 16 being fixed to the main frame at the front thereof. 85

The front end of the front truck section projects beyond the front of the main frame and receives an idler sprocket wheel 17 at 90 its forward end. An endless chain track 18 is carried by the front and rear sprocket wheels 11 and 17 and forms at its ground stretch a track upon which the flanged rollers 15 operate. The hinged connection between the front and rear truck sections is by means of a stub shaft or pin 19, opposite trucks being not connected together transversely at this point. The construction is such that the truck frame members will 95 move downwardly away from the main frame at their joint 19 to a degree sufficient to insure the full tractive effect of the chain track in passing over depressions, and the like, and also to permit the front truck section to move upwardly in a vertical plane about its pivotal connection with the main frame to an angle greater than 45° with respect to the plane of the rear section, so that embankments may be climbed without dan- 100 105 110

ger of the front portion of the track digging into the earth.

In order to permit this flexing of the truck sections, I connect the rear section 5 slidably and pivotally with the main frame at a point near the rear end of the said truck section. This may be done in any one of several improved ways, two such being illustrated herewith. In Fig. 5 this is accomplished by supporting the main frame upon the rear truck section through a V-shaped block 20, carried on the end of a cross sill 21 and employing spaced clips 22 depending from said sill, one at each side 10 of the truck frame to engage beneath flanges 23 on the latter. This connection not only permits pivotal and slidable movement of the truck frame member relative to the main frame but it also prevents the said truck 15 from dropping away from the main frame 20 when the track chain sags.

In Fig. 1, I show a modified form of connection consisting of a flanged roller 24 journaled upon the main frame near the 25 rear end thereof and resting upon the top of the rear truck frame member. This permits the desired pivotal and slidable movement and has the advantage of overcoming friction. Except for the slidable and pivotal 30 connection at the rear and the pivotal connection at the front, the hinged truck frame is free of the main frame and is capable of assuming almost any upwardly diverging angular position to suit the 35 contour of the ground.

In order to secure the advantage of a spring mounting for the main frame, I arrange a pair of helical compression springs 25 beneath each side of the main frame, forwardly of the slidable and pivotal connection of the rear truck section, said springs, when the truck section is in normal position, resting upon the top of the latter and cushioning the main frame. These springs are 40 secured in place to the main frame and disconnected from the truck frame so that the latter will be free to move downwardly as far as the position of the track will permit. Also the front end of the main frame is 45 resiliently supported upon the front truck sections by means of a yielding bearing for the ends of the transverse shaft 16. This bearing comprises a block 26 receiving the end of the shaft and having fore and aft extending arms 27 resting upon the helical compression springs 28 seated on the truck frame. An upwardly projecting member 29, on the truck frame, has a vertical slot 30 slidably receiving the block 26 on the shaft 50 and serves to rigidly connect the shaft and truck frame in a fore and aft direction while permitting relative movement vertically in line with the yielding movements of the 55 springs.

60 For greater strength and rigidity, I may

employ a push-rod 32, on each end of the driving shaft 12, extending forwardly and connected with the projecting end of the cross sill 21. Also a thrust member 33 is adjustably secured to the member 29 at each 65 side of the machine and extends forwardly to the adjacent idler wheel 17, being connected to the bearings 33^a of the latter. Said bearings are adjustable back and forth upon the front frame member to change the 70 position of the front idler wheel, whereby to tension the track. Supports for the upper run of the chain track may be in the form of a series of rollers 34 journaled on supports fixed to the side of the main frame, 75 while the track immediately behind the front idler wheel is supported upon a separate roller 35 carried by the thrust member 33 and being, therefore, movable with the 80 front end of the truck.

85

A motor 36, located at any desired point on the main frame, operates the rear driving wheels 11 through the medium of suitable change speed transmission mechanism 37, whereby to propel the machine. A friction 90 clutch 38 is interposed between the transmission and driving axle of each side and steering is effected by varying the relative speeds of the two tracks, brake mechanism 39 being employed to hold one track stationary while the other is in operation.

In operation, the truck sections will flex or sag as is desired to negotiate ditches, shell holes, and the like, and thereby the track will be kept in engagement with the ground 100 throughout its full length. The hinged sections are capable of assuming any relative position varying from a straight line to an upwardly diverging angle of approximately 135°. In so flexing, however, the track will 105 not have any appreciable amount of slack, since the rear driving wheel is held in fixed position and the slack caused by the movement of the front wheel toward the rear wheel will be taken up by the deflection of 110 the truck frame members at the bottom of the track. The front truck sections projecting as they do considerably forward of their pivotal connections with the main frame, and, being free to turn on the shaft 16, will 115 tilt upwardly when meeting an embankment and assume an inclination sufficient to permit the track to climb a vertical rise without liability of digging into the earth.

In certain conditions of ground, as, for 120 instance, where narrow and deep ditches or trenches are encountered, the flexing of the truck sections will not serve any advantageous purpose and it is preferable to lock them so that the truck frames become rigid. 125 This can be done by various means, one such being shown as comprising a hook-shaped lug 40 on the joint of each truck frame and a pendent hook-shaped pawl 41 to coöperate therewith, said pawl being pivoted to the 130

main frame and operated by means of a lever 42 adjacent to the driver's seat. Opposite pawls can be connected together by means of a shaft 43 so that a single lever 5 will serve to operate both. These pawls normally will be out of engagement with their lugs and the truck sections at such times are free to flex. However, when conditions warrant the pawls offer a ready 10 means of locking the truck sections against downward movement at their joints.

The springs 25, on the rear truck sections, cushion the shocks, due to the sudden upward movement of the said sections, and the 15 spring mountings for the shaft 16 cushion the shocks which occur when the front end of the machine strikes the ground after passing over a sharp rise. Each truck, in so far as its flexing is concerned, is independent of 25 the other and, therefore, is free to conform to conditions of ground which may be wholly dissimilar to the conditions of the ground over which the opposite truck is passing.

25 While articulated and rocking truck members have been employed before in tractors of the self-playing track type, as shown and described in Patent No. 1,184,705 to Emil F. Norelius dated May 23rd, 1916, yet the flexing 30 of the truck members was more or less limited and not intended to fit any such extreme conditions as the present device will operate under.

Various changes in the construction and 35 arrangement of the several parts herein shown and described may be made without departing from the spirit of my invention as disclosed in the appended claims. Thus for instance in Fig. 6 an alternative structure is 40 illustrated in which the rear truck section 14 is pivoted at 21^a similarly to the pivot construction 16 of the forward truck section 13, previously described. The allowance 45 for articulation between the two truck sections is provided by means of a bracket 10^a and link 10^b; the link 10^b providing for the necessary straightening and bending of the sections.

It is manifest that the method of mounting 50 and articulating the truck sections and arranging the front and rear sprockets so that they move toward and from each other in unison with the change in angularity of the truck sections that the track belt is maintained at all times in operative position without danger of the track belt climbing 55 the sprockets or leaving the truck sections no matter what pitch the truck sections assume.

Having thus described my invention, what 60 I claim and desire to secure by Letters Patent is—

1. In a vehicle, a main frame, articulated 65 roller truck mechanism for supporting the same, a self-laying track upon which the

roller truck mechanism operates, and fixed connections between the truck mechanism and the main frame permitting vertical rocking movement of the articulated sections, whereby they may assume different 70 relative positions varying from a straight line to an upwardly diverging angle of approximately 135°, whereby to conform to the contour of the ground over which they are passing.

2. In a vehicle, the combination of a main frame, an endless, self-laying track, a truck supported within the track and carrying the weight of the main frame, said truck including a plurality of separate sections, and 80 a fixed pivotal connection between each truck section and the main frame such that the sections may rock freely in a vertical plane to assume various relative positions from a straight line to an upwardly diverging angle of approximately 135°.

3. In a vehicle, the combination with a frame, of a pair of self-laying tracks adapted to support the weight of the frame, trucks interposed between the frame and the tracks, each truck comprising a plurality of separate sections, a fixed pivotal connection between each truck section and the main frame permitting oscillating movement in a vertical plane, and a hinged connection between the adjacent ends of said truck sections, whereby the movements imparted to one section by variations in the surface of the ground are also imparted to the other section.

4. In a tractor of the self-laying track type, a main frame, and a jointed truck frame for supporting the main frame and fitted with rollers operating upon the ground stretch of the track, pivotal connections between the main frame and the opposite ends of the truck frames, said truck frame being disconnected from the main frame intermediate its ends and free to move away from the latter at its joint, whereby 105 to permit the track to conform to depressions in the ground.

5. In a tractor of the self-laying track type, a main frame, front and rear truck frame members for supporting the main frame, each frame member being fitted with rollers adapted for operation upon the ground stretch of the track, a driving sprocket wheel at the rear of main frame upon which the chain track rides, a guide 115 wheel for the front end of the track journaled upon the front end of the front truck member, and a fixed pivotal connection between the front truck frame member and the main frame permitting upward movement 120 of the forward portion of the front truck frame member to an angle of approximately 45° with the plane of the rear truck frame member.

6. In a tractor of the self-laying track 130

4.

type, a main frame, front and rear truck frame members for supporting the main frame, each frame member being fitted with rollers adapted for operation upon the 5 ground stretch of the track, a driving sprocket wheel at the rear of the main frame upon which the chain track rides, a guide wheel for the front end of the track journaled upon the front end of the front truck 10 member, said truck frame members being hinged together at their adjacent ends, and fixed pivotal connections between each member and the main frame permitting them to flex downwardly at their adjacent ends to 15 assume an angle of approximately 135°.

7. In a tractor of the self-laying track type, a main frame, a sectional truck frame for supporting the main frame, each truck frame being fitted with rollers for operation 20 upon the ground stretch of the track, and connections between each truck frame section and the main frame permitting rocking movement in a vertical plane such that the truck frame sections may assume different angular relations varying from a straight line to an upwardly diverging angle 25 of approximately 135° in passing over depressions in the ground.

8. In a vehicle, the combination of a main 30 frame and an endless, self-laying track mechanism comprising a two-part roller truck, a sprocket wheel thereon, a sprocket wheel on the main frame, a track riding over said sprocket wheels and supporting the 35 truck, a pivotal connection between the front truck member and the main frame, a pivotal and slideable connection between the rear truck member and the main frame, and hinged connections between the two truck 40 members, said connections being so arranged that both truck members will rock in a vertical plane about their pivotal connection with the main frame.

9. In a vehicle, the combination of a main 45 frame and an endless, self-laying track mechanism comprising a two-part roller truck, a sprocket wheel thereon, a sprocket wheel on the main frame, a track riding over said sprocket wheels and supporting the 50 truck, a pivotal connection between the front truck member and the main frame, a pivotal and slideable connection between the rear truck member and the main frame, hinged connections between the two truck members, 55 said connections being so arranged that both truck members will rock in a vertical plane about their pivotal connection with the main frame, the pivotal and slideable connection for the rear truck member being located 60 near the rear end thereof, and springs carried by the main frame and resting detachably upon the front portion of the rear truck member to absorb the shocks due to upward movement of the forward portion of the rear 65 truck member.

10. In a vehicle, the combination of a main frame and an endless, self-laying track mechanism comprising a two-part roller truck, a sprocket wheel thereon, a sprocket wheel on the main frame, a track riding over 70 said sprocket wheels and supporting the truck, a pivotal connection between the front truck member and the main frame, a pivotal and slideable connection between the rear truck member and the main frame, 75 hinged connections between the two truck members, said connections being so arranged that both truck members will rock in a vertical plane about their pivotal connection with the main frame, and a spring bearing 80 for the pivotal connection between the front truck member and the main frame to cushion the main frame.

11. In a vehicle, a main frame, articulated roller truck mechanism for supporting the 85 same, an endless track upon which said truck mechanism travels, and connections between the opposite ends of said truck mechanism and the main frame permitting the latter to move freely in a vertical direction 90 at its joint, whereby to conform to the contour of the ground.

12. In a vehicle, a main frame, articulated roller truck mechanism for supporting the same, an endless track upon which said 95 truck mechanism travels, connections between said truck mechanism and the main frame permitting the latter to move freely in a vertical direction at its joint, whereby to conform to the contour of the ground, and 100 means for locking said joint so that the truck mechanism becomes rigid.

13. In a vehicle, a main frame, a two-part roller truck mechanism for supporting the main frame, an endless, self-laying track 105 upon which said truck mechanism travels, connections between the sections of said truck mechanism and the main frame, whereby to permit said truck sections to move downwardly away from the main 110 frame at their adjacent ends, and means on the main frame engageable with the truck sections to retain the latter against downward movement.

14. In a vehicle, a main frame, a two-part 115 roller truck mechanism for supporting the main frame, an endless self-laying track upon which said truck mechanism travels, a fixed pivotal connection between the front section of said roller truck mechanism and 120 the main frame, and connecting means between the rear truck section and the main frame for allowing vertical swinging movement thereof.

15. In a vehicle, a main frame, an articulated roller truck mechanism for supporting the same, an endless track upon which said truck mechanism travels, means for pivoting the forward section of said truck mechanism to the main frame to permit it 125 130

to swing in relation to a fixed axis, and a connection between the main frame and the rear end of the rear section of the truck mechanism for permitting it to swing in relation to the main frame and in relation to the front section of the truck mechanism. In testimony whereof I have hereunto set my hand in the presence of two subscribing witnesses.

PLINY E. HOLT.
